AWNNG

Edward Reukauf, Jr., and Walter J. Stuber, Philadelphia, Pa., assignors to Carey-McFall Co., Philadelphia, Pa., a corporation of Pennsylvania

Application October 10, 1934, Serial No. 747,792

13 Claims. (Cl. 156—44)

The invention relates to outside sun awnings for house windows and its primary purpose or object is to eliminate the necessity for ropes, pulleys and other means commonly employed for adjusting the awning to various positions.

Another object of the present invention is to facilitate the hanging and taking-down of awnings, by eliminating the tiresome screw eye and eyelet method commonly employed for hanging awnings.

Another object of the invention is to provide a spring-loaded roller for raising the awning and means for insuring that the roller spring is wound to the proper extent to function properly under conditions of use.

The construction and operation of the awning assemblage will be fully disclosed hereinafter, reference being had to the accompanying drawings; of which:

20 Fig. 1 shows the awning in perspective, in a partially raised position;

Fig. 2 is a detached perspective view of the awning taken down and partially disassembled for storage or shipping purposes;

25 Fig. 3 is a longitudinal sectional view of the roll frame and spring-loaded roller assemblage, taken on the line 3—3, Fig. 2;

Fig. 4 is a vertical sectional elevation of the locking mechanism taken on the line 4—4, Fig. 1;

30 Figs. 5 and 6 are respectively a plan and an inverted plan view of the mechanism shown in Fig. 4; and

Fig. 7 is a detail of the invention.

Secured to the window frame 1, Fig. 1, is a series of brackets 2, each provided with a spring tongue 3 pressed outwardly from the bracket 2 and providing a space 4 for the reception of a roller-supporting frame 5, which latter is adapted to extend across the full width of the window frame, the series of brackets 2 firmly supporting the frame 5 at the top of the window.

The frame 5 is provided with outwardly extending arms 6, 6 at its opposite ends respectively which are arranged at 90° to the body of the frame 5 to support the trunnions 7 and 8 of a spring roller 9, one of the arms 6 being provided with a circular opening 10 for receiving the corresponding round trunnion 7 of the roller while the other of the arms 6 is provided with an elongated slot 11 for the reception of the second trunnion 8, which latter is flattened and fits the slot 11 in a manner to prevent the trunnion 11 from turning in the arm 6.

5 The roller 9 is provided with the usual spring

12 having one end secured to the trunnion 11 and its opposite end secured to the roller 9 and constantly tending to rotate the roller 9 over the top toward the frame 5, to wind the awning 15 on the roller.

One edge of the awning 15 is secured to the roller 9 while the opposite edge is provided with a hem 16 for the reception of the cross bar 17 of the awning frame 18. Each of the opposite ends of the cross bar 17 is detachably secured to 16 a side bar 19 of the awning frame as by a cotter pin or other readily removable means 14. The awning frame is similar in construction to that shown and described in the applicant's copending application, Serial No. 747,793, filed October 15, 1934.

The opposite end of each side bar 19 is rigidly secured to one arm 20 of the bell-crank lever 21. Each bell-crank lever 21 is pivoted at 22 to a pair of arms 23 forming part of a bracket 24 20 which is secured by screws 25, 25 to the window frame 1.

Pivots attached at 26 to the second arm 27 of each bell-crank lever 21 is a ratchet bar 28, provided adjacent its lower end with any desired 25 number of ratchet teeth 29 adapted to be singly engaged by a pawl 30 on and forming part of a holding latch 31.

Each of the holding latches 31 is pivoted at 32 to the lower end of the bracket 24 and each 30 of the latches 31 adjacent the pawl 30 is provided with an opening 33 through which the lower end of the ratchet bar 28 extends.

Intermediate the side arms 34, 34 of the latch 31 and encircling the pivot pin 32 of the latch is 35 a spring 35, one end of which bears against the front face of the bracket 24 while the opposite end bears on the upper edge of the latch 31 and tends to swing the latch 31 downwardly about its pivot 32 to hold the pawl 30 in each instance 40 in one of the notches 29 of the cooperating ratchet bar 28, downward movement of the latch 31 in each instance being limited by the outer end of the latch opening 33 engaging the edge of the ratchet bar 28 opposite to that in which 45 the notches 29 are formed.

The spring 12 in the roller 9 tends to wind the awning 15 thereon at all times which tends to swing the frame 18 upwardly in the direction of the arrow x, Fig. 4, which in turn tends to move 50 the ratchet bar 28 downwardly in the direction of the arrow y, Fig. 4, but due to the pawl 30 being in engagement with one of the notches 29 and the outer end of the slot 33 in the latch 31 being in engagement with the outer edge of the 55

ratchet bar 28 downward movement of the ratchet bar 28 is prevented, whereby the awning is held firmly in the position to which it is adjusted.

4 The awning may be readily lowered by swinging the frame 18 in a direction opposite to that indicated by the arrow x in which case the ratchet bar 28 moves upwardly through the slot 33 of the latch 31 and the spring 35 tends to 10 click the pawl 30 into each of the notches 29 as the ratchet bar 28 is moved upwardly.

In order to raise the awning 15 the latches 31 are swung upwardly as indicated by the arrow z in Fig. 4 which releases the pawl 30 from the notches 29 and permits the bar 28 to slide freely, downwardly through the slot 33, as long as the latch 31 is held in a raised position. The spring 12 in the roller 9 under such circumstances swings the awning frame 18 about its pivots 22 until the 20 awning 15 is completely wound on the roller 9.

The side arms 19 of the awning frame 18 are hollow in the present instance, and the lower end of each arm 19 fits into a correspondingly rounded end or socket 36 formed on the arm 20 of the bell-crank lever 21, the hollow rod 19 and the extension 36 of the bell-crank lever 21 being drilled for the reception of fastening means such as cotter pins or rivets 38 passing through both and securing the two in fixed relation to each other.

The front rod 17 may be solid or hollow and formed with solid or hollow elbow ends 37 provided with projections 39 adapted to fit into the outer ends of the hollow side arms or rods 19 35 to be secured together by the cotter pins 14 in the same general manner as the inner ends of the rods 19 are secured in the sockets 36 of the bell-crank levers 21 by the cotter pins or rivets 38. However, the front bar 17 and corner members 37 are preferably constructed and joined in the same manner as disclosed in the above noted 40 coperating application.

The front rod 17 is held against longitudinal movement in the hem 16 of the awning 15 by 45 any suitable means and in the present instance, for this purpose, a screw 40 is passed through the material of the awning 15 or the hem piece 16 thereof and threaded into a tapped hole in the rod 17, as shown in Figs. 1 and 7.

50 In shipping, the parts are assembled and packaged as in Fig. 2, the awning being wound completely on the roller 9, by the tension of the spring 12, until the elbow pieces 37 bear against the arms 6, 6 of the frame 5. For the purpose of 55 clearness the awning in Fig. 2 is shown as being slightly unwound from the roller.

The roller trunnions 7 and 8 are not readily removable from the arms 6, 6 of the frame 5, thus the manufacturer in shipping the awning 60 may be assured that when the awning is hung the spring 12 will be under the necessary amount of tension to function properly.

In hanging the awning, the brackets 2, 2 are first secured on the top of the window frame 1 65 in proper relation to each other to receive the roller frame 5.

The side arms 19, 19 may be attached to the front rod 17 either before or after the frame 5 is snapped into place behind the tongues 3 of the brackets 2. In either case the frame 5 is snapped into position and if the arms 19, 19 have not been previously applied they may now be joined to the front rod 17 and secured thereby by inserting the cotter pins 14. This leaves the side rods 19, 19 hanging downwardly at the opposite 75

sides respectively of the window frame, with the brackets 24, 24 attached to the lower ends of the side arms.

The person hanging the awning, upon determining how low he wishes the awning to come 5 when fully extended will then secure the brackets 24, 24 in place at the same and proper distance above the window sill to obtain the desired degree of screening by the awning. The awning is then ready for use and can be lowered to any 10 desired position, depending upon the number of notches 29 in the ratchet bars 28, by merely swinging the side arms about their respective pivots simultaneously. The pawls or latches 31 will arrest upward movement of the awning 15 immediately upon release of the downward and outward pressure exerted against the arms 19.

In taking down the awning all that is necessary is to remove the cotter pins 14 when the awning is completely wound on the roller 9 and 20 then to raise the roller frame 5 out of the hooks formed by the tongues 3 of the brackets 2, at the same time slipping the projections 39 of the front rod 17 upwardly out of the upper ends of the side arms 19 of the awning frame 18. The 25 pivot and locking brackets 24, 24 and the roller brackets 2, 2 may be easily removed from the window frame 1 and the whole assembled compactly for storage or for reshipping purposes.

The hanger brackets 2 and the locking brackets 30 24 may be left in place on the window frame during the winter season if desired, in which case the rivets 38 which secure the inner or lower ends of the side arms 19, 19 in the sockets 36 of the bell-crank levers 21 would be replaced by readily 35 removable bolts or cotter pins.

We claim:

1. The combination of an awning, a roller to which one end of the awning is secured, an awning adjusting member to which the opposite end 40 of the awning is secured, a rigid frame rotatably supporting the roller, and a spring under definite predetermined tension rotating the roller and winding the awning thereon until said awning 45 adjusting member engages said rigid frame and prevents further awning winding rotation of the roller, said roller and rigid frame, said roller and awning, and said awning and adjusting frame member constituting a normally inseparable unit preserving said definite tensioning of the spring. 50

2. The combination of an awning, a roller to which one end of the awning is secured, an awning adjusting member projecting beyond the opposite side edges of the awning and to which the opposite end of the awning is secured, a rigid 55 frame comprising a bar substantially paralleling the axis of the roller and a pair of trunnion bearing brackets integral with and extending laterally from said bar and rotatably supporting the roller, and a spring under definite predetermined 60 tension rotating the roller and winding the awning thereon until the projecting ends of said awning adjusting member engages said rigid frame trunnion bearing brackets and prevents further awning winding rotation of the roller, 65 said roller and rigid frame, said roller and awning, and said awning and adjusting frame member constituting a normally inseparable unit preserving said definite tensioning of the spring.

3. The combination of an awning, a roller to 70 which end of the awning is secured, an awning adjusting member projecting beyond the opposite side edges of the awning and to which the opposite end of the awning is secured against relative movement therebetween transversely of 75

th awning, a rigid frame comprising a bar substantially paralleling the axis of the roller and a pair of trunnion bearing brackets integral with and extending laterally from said bar and rotatably supporting the roller, and a spring under definite predetermined tension rotating the roller and winding the awning thereon until the projecting ends of said awning adjusting member engages said rigid frame trunnion bearing brackets and prevents further awning winding rotation of the roller, said roller and rigid frame, said roller and awning, and said awning and adjusting frame member constituting a normally inseparable unit preserving said definite tensioning of the spring.

4. The combination of an awning, a roller to which one end of the awning is secured, an awning adjusting member projecting beyond the opposite side edges of the awning and to which the opposite end of the awning is secured against relative movement therebetween transversely of the awning, a rigid frame comprising a bar substantially paralleling the axis of the roller and a pair of trunnion bearing brackets integral with and extending laterally from said bar and rotatably supporting the roller, a spring under definite predetermined tension rotating the roller and winding the awning thereon until the projecting ends of said awning adjusting member engage said rigid frame trunnion bearing brackets and prevent further awning winding rotation of the roller, said roller and rigid frame, said roller and awning, and said awning and adjusting frame member constituting a normally inseparable unit preserving said definite tensioning of the spring, supporting brackets for said rigid frame comprising resilient tongues forming hooks engaging and supporting said bar, side arms having outer ends respectively and detachably secured to the oppositely projecting ends of said awning adjusting member, brackets remotely situated with respect to said bar-supporting brackets and pivotally supporting the inner ends of said side arms respectively, and pawl and ratchet mechanism carried by said pivot brackets and side arms respectively and maintaining the adjusting member end of the awning in any one of a number of positions outwardly extended from said roller in accordance with an angular position of the side arms attained by swinging said arms simultaneously around their respective pivots.

5. The combination of an awning, a roller to which one end of the awning is secured, an awning adjusting member projecting beyond the opposite side edges of the awning and to which the opposite end of the awning is secured against relative movement therebetween transversely of the awning, a rigid frame comprising a bar substantially paralleling the axis of the roller and a pair of trunnion bearing brackets integral with and extending laterally from said bar and rotatably supporting the roller, a spring under definite predetermined tension rotating the roller and winding the awning thereon until the projecting ends of said awning adjusting member engage said rigid frame trunnion bearing brackets and prevents further awning winding rotation of the roller, said roller and rigid frame, said roller and awning, and said awning and adjusting frame member constituting a normally inseparable unit preserving said definite tensioning of the spring, supporting brackets for said rigid frame comprising resilient tongues forming hooks engaging and supporting said bar, side arms having outer ends respectively and detachably secured to the op-

positely projecting ends of said awning adjusting member, brackets remotely situated with respect to said bar-supporting brackets and pivotally supporting the inner ends of said side arms respectively, pawl and ratchet mechanism carried by said pivot brackets and side arms respectively and maintaining the adjusting member end of the awning in any one of a number of positions outwardly extended from said roller in accordance with an angular position of the side arms attained by swinging said arms simultaneously around their respective pivots, and means for disengaging said pawl and ratchet mechanisms to permit rewinding of the awning on and by said rotation of the roller.

6. The combination of an awning, a spring-loaded roller having one end of the awning secured thereto and winding the awning thereon, an awning adjusting frame attached to and supporting the opposite end of the awning, brackets remote to the roller and affording pivotal support for the adjusting frame, a ratchet bar pivotally mounted on the adjusting frame adjacent the pivot thereof, a pawl carried by each of the brackets, and resilient means effecting cooperative engagement between the pawl and ratchet bar to maintain the adjusting frame in any one of a number of awning extending positions relative to the roller.

7. The combination of an awning frame comprising a side arm, a bracket pivotally supporting said side arm, a lever extension on said side arm, a ratchet bar pivoted to said lever extension, a pawl pivoted to said bracket, and resilient means maintaining cooperative engagement between the ratchet bar and the pawl for maintaining the side arm in any one of a number of angular positions radially disposed to the axis of the side arm pivot.

8. The combination of an awning frame comprising a side arm, a bracket affording pivotal support for said side arm, a latch lever pivoted to said bracket in spaced relation to the side arm pivot longitudinally of the bracket, a bar having one end pivoted to said side arm and extending to and beyond said latch lever, a portion of said latch lever being arranged to enter any one of a number of recesses in said bar for maintaining the side arm in a predetermined position about the axis of the side arm pivot.

9. The combination of an awning frame comprising a side arm, a bracket affording pivotal support for the side arm, a latch lever pivoted to the bracket in spaced relation to the side arm pivot longitudinally of the bracket, a bar pivoted at one end to the side arm and extending through an opening in said latch lever, one edge of said opening being arranged to enter any one of a number of recesses formed in the adjacent edge of the bar, for maintaining the side arm in a predetermined position about the axis of the side arm pivot.

10. The combination of an awning frame comprising a side arm, a bracket affording pivotal support for the side arm, a latch lever pivoted to the bracket in spaced relation to the side arm pivot longitudinally of the bracket, a bar pivoted at one end to the side arm and extending through an opening in said latch lever, one edge of said opening being arranged to enter any one of a number of recesses formed in the adjacent edge of the bar, the opposite edge of the latch lever opening engaging the opposite edge of the recessed bar, for maintaining the side arm in a predetermined position about the axis of the side arm pivot.

11. The combination of an awning frame comprising a side arm, a bracket affording pivotal support for the side arm, a latch lever pivoted to the bracket in spaced relation to the side arm 5 pivot longitudinally of the bracket, a bar pivoted at one end to the side arm and extending through an opening in said latch lever, one edge of said opening being arranged to enter any one of a number of recesses formed in the adjacent edge 10 of the bar, the opposite edge of the latch lever opening engaging the opposite edge of the recessed bar, and resilient means rocking the latch lever about its pivot to effect said cooperative engagement between said latch lever and bar edges.
12. The combination of an awning frame comprising a side arm, a bracket comprising a base and an outwardly projecting lug affording pivotal support for said side arm, a lever extension on said side arm projecting from the pivot of the side arm toward said bracket base, a latch lever 15 pivoted to said bracket below said side arm pivot in spaced relation thereto longitudinally of said bracket, a bar pivotally connected at one of its ends to the inwardly extending end of said lever extension with its opposite end hanging downwardly through an opening formed in said latch lever, the inner edge of said latch lever opening being arranged to enter any one of a series of notches formed in the inner edge of said bar 20 and the outer edge of said opening engaging the outer edge of said bar, and a spring turning the latch lever on its pivot to maintain said edge engagement 25
- 30

gagements resiliently and prevent swinging movement of the side arm in one direction but permitting swinging movement thereof in the opposite direction.

13. The combination of an awning frame comprising a side arm, a bracket comprising a base and an outwardly projecting lug affording pivotal support for said side arm, a lever extension on said side arm projecting from the pivot of the side arm toward said bracket base, a latch lever 10 pivoted to said bracket below said side arm pivot in spaced relation thereto longitudinally of said bracket, a bar pivotally connected at one of its ends to the inwardly extending end of said lever extension with its opposite end hanging downwardly through an opening formed in said latch lever, the inner edge of said latch lever opening being arranged to enter any one of a series of notches formed in the inner edge of said bar and the outer edge of said opening engaging the outer edge of said bar, a spring turning the latch lever on its pivot to maintain said edge engagement 15 resiliently and prevent swinging movement of the side arm in one direction but permitting swinging movement thereof in the opposite direction, and a finger grip on the outer end of said latch lever for effecting release of said edges to permit swinging of the side arm about its pivot in the first said direction.
